UNITED STATES PATENT OFFICE.

FRANK M. MORTON, OF PHENIX CITY, ALABAMA.

CALENDER RACK.

Application filed January 10, 1927. Serial No. 160,292.

The invention relates to calender racks for holding lap pins normally in proper position, but for releasing and permitting upward movement of the pin in case excessive pressure is exerted by the latter. Calender racks of this general nature have of course heretofore been used, both with slideable and pivoted heads carrying lap pin bearings. It is the object of my invention 10 however to provide a new and improved form of calender rack which possesses a number of novel and advantageous features of construction.

With the foregoing in view, the invention resides in the novel subject matter hereinafter described and claimed, the description being supplemented by the accompanying drawing.

Fig. 1 is a vertical sectional view partly 20 in elevation of a calender rack constructed in accordance with the present invention, the device being disposed for holding the lap pin in its normal position.

Fig. 2 is a view similar to Fig. 1 but 25 illustrating the manner in which the device permits upward shifting of the lap pin under excessive pressure.

Fig. 3 is an edge view as indicated by the arrow A of Fig. 1.

Fig. 4 is a detail sectional view on the plane of line 4—4 of Fig. 1.

The drawings above briefly described, illustrate the preferred form of construction and while this construction will be herein-after specifically described, it is to be understood at the outset that the disclosure is illustrative rather than limiting, in most respects.

The numeral 5 designates a vertical rack 40 having the usual teeth 6. Formed integrally with the upper end of this rack, is a substantially semi-cylindrical hood 7 which opens laterally and is provided at its upper portion with an integral, outwardly projecting tubular neck 8, an opening 9 being formed from the interior of the neck to the interior of the hood.

A hood-like head 10 is received between the side members 11 of the hood 7 and is 50 provided with a curved peripheral wall 12 which extends across the opening 9, the side members 13 of said head being in or substantially in contact with the side members 11 of the hood 7. It will be observed from 55 Fig. 1, that the interiors of the hood 7 and head 10 are in communication with each

other, and that said interiors receive a main, lap pin bearing roller 14 whose periphery is downwardly exposed at one edge of the rack 5. A single pin 15 passes through the side members 11 and 13 and through the roller 14, to pivotally connect the head 10 with the hood 7 and to rotatably mount the roller 14.

At the lower end of the peripheral wall 65 12, a second lap pin bearing roller 16 is rotatably mounted between the side members 13, and this roller maintains the lap pin 17 in contact with the roller 14, at the same time, assisting in forming an adequate 70 roller bearing for said pin. Preferably, the side members 13 have downwardly extended portions 18 which project below the roller 16 and constitute noses for holding the lap pin 17 in engagement with the rollers, whenever 75 the head 10 turns about its pivot 15, under excessive pressure on the lap pin.

The head 10 is normally held against turning about the pivot 15, by a spring-pressed shoe 19 disposed in the opening 9 and normally abutting a shoulder 20 on the wall 12, said shoulder being preferably formed by one side wall of a groove. The shoe 19 is by preference in the form of a roller and it is engaged by a grooved disk 21 within 80 the neck 8. A coiled compression spring 22, within this neck, contacts at one end with the disk 21 and at its other end engages another disk 23. A screw 24 having an operating handle 25, is threaded through a closure 90 26 for the outer end of the neck 8 and contacts with the disk 23, thus permitting the proper strength to be normally stored in the spring 22, for the purpose of holding the shoe 19 engaged with the shoulder 20. However, 95 when the lap pin 17 forces upwardly upon the rollers 14 and 16 with excessive pressure, the strength of the spring 22 is overcome and the shoe 19 then disengages from the shoulder 20, permitting the head 10 to turn 100 as shown in Fig. 2. During this turning movement, the lap pin 17 travels along the periphery of the roller 14, due to the fact that head 10 is pivotally mounted co-axially with this roller. During this turning of the head 10, its arcuate peripheral wall 12 forms a track along which the shoe 19 travels, and said wall is provided with means for impeding the shoe, thus creating a braking 105 action to control the swinging of the head 110 10 and prevent it from immediately flying upwardly to maximum extent upon release.

of the shoe 19 from the shoulder 20. In the present showing, this impeding means is formed by circumferentially spaced transverse grooves 27 in the wall 12, sides of said 5 grooves forming shoulders which are successively engaged by the shoe.

When no more than normal upward pressure is exerted upon the rollers 14 and 16 by the lap pin 17, the parts will remain in 10 the relation shown in Figs. 1 and 2, but when the upward pressure is excessive, the spring 22 is overcome, permitting disengagement of the shoe 19 from the shoulder 20 and allowing turning of the head 10 15 about its pivot 15. During this turning, a braking action is created on the head 10 by the co-operation of the shoe 19 with the grooves or the like 27, and as such turning takes place, the lap pin 17 remains in 20 engagement with the rollers 14 and 16, merely traveling along the periphery of the former, until possibly the maximum upward position of the head is reached.

To reset the device from a released position, it is simply necessary to loosen the 25 screw 24 by means of the handle 25, whereupon head 10 may be easily swung to its normal position, in which position it will be held by the shoe 19 and shoulder 20, when the 30 screw is again tightened.

The details herein disclosed are advantageous and may well be followed. However, in this connection, attention is again invited 35 to the fact that within the scope of the invention as claimed, numerous variations may be made.

I claim:

1. A device of the class described comprising a rack, a lap pin bearing roller 40 mounted thereon, a head pivoted to the rack co-axially with said roller and having means laterally offset from the roller for holding a lap pin against said roller, and yieldable means for holding the head against pivotal 45 movement until the lap pin exerts excessive pressure against said lap pin holding means thereof, said yieldable means then permitting pivotal movement of the head and travel of the lap pin around the periphery 50 of said roller.

2. A device of the class described comprising a rack, a lap pin bearing roller mounted thereon, a head pivoted to said rack co-axially with said roller, a second lap pin bearing roller spaced laterally from the lower 55 portion of the first named roller and mounted on said head, and yieldable means for holding said head against pivotal movement until the lap pin forces with excessive pressure against the rollers, said means yielding under such excessive pressure, permitting turning of the head and travel of the lap pin around the periphery of the first named 60 roller.

3. A structure as specified in claim 2;

said head having a nose projecting downwardly beyond the second roller to hold the lap pin engaged with the rollers as the head turns about its pivot.

4. A device of the class described comprising a rack, a lap pin bearing roller, a head provided with means for holding a lap pin against said roller, a single pin pivoting said head to the rack and rotatably connecting the roller with said rack, and yieldable means for holding the head against pivotal movement until the lap pin forces with excessive pressure against the lap pin holding means of said head. 70

5. A device of the class described comprising a rack, a head pivoted to said rack on a transverse axis and having a lap pin bearing laterally offset from its pivot, said head being provided with a track substantially concentric with its pivot and formed 85 with a shoulder, and a yieldable shoe mounted on the rack and engaging said shoulder; the shoe and shoulder serving to hold the head against pivotal movement until excessive pressure is exerted against said bearing by the lap pin, whereupon the shoe disengages from the shoulder and moves along said track, said track being provided with longitudinally spaced impediments 90 successively engaged by the shoe to create a 95 braking action controlling the pivotal movement of the head.

6. A device of the class described comprising a rack having a laterally opening rigid hood at its upper end, a tubular neck projecting rigidly outwardly from said hood and an opening from the interior of the neck to the interior of the hood; a hood-like head between the side members of the hood and having a curved peripheral wall extending across the aforesaid opening, the interiors of the hood and head being in communication with each other, a lap pin bearing roller in said interiors, a pin passing through the side members of the hood and head and through the roller to pivotally connect said hood and head and rotatably mount the roller, the aforesaid curved peripheral wall being substantially concentric with said pin, said head having means laterally offset from said roller for holding a lap pin against the same, a shoe in the above-named opening engaging the aforesaid curved peripheral wall, the latter having a shoulder normally abutting said shoe, and spring means mounted in the above named tubular neck for holding the shoe engaged with said shoulder until the lap pin forces with excessive pressure against the lap pin holding portion of the head. 100

7. A device of the class described comprising a rack having a laterally opening rigid hood at its upper end, a tubular neck projecting rigidly outwardly from said hood and an opening from the interior of the neck 105 110 115 120 125 130

to the interior of the hood; a hood-like head between the side members of the hood and having a curved peripheral wall extending across the aforesaid opening, the interiors of the hood and head being in communication with each other, a lap pin bearing roller in said interiors, a pin passing through the side members of the hood and head and through the roller to pivotally connect said hood and head and rotatably mount the roller, the aforesaid curved peripheral wall being substantially concentric with said pin, a second lap pin bearing roller mounted between the side members of the head and laterally offset from the first named roller for holding a lap pin against the same, a shoe in the above named opening engaging the aforesaid

curved peripheral wall, the latter having a shoulder normally abutting said shoe, and spring means mounted in the above-named tubular neck for holding the shoe engaged with said shoulder until the lap pin forces with excessive pressure against said second lap pin bearing roller.

8. A structure as specified in claim 7; said side members of said head having portions projecting downwardly beyond said second roller to engage the lap pin and hold it against movement from the rollers as the head turns about its pivot pin.

In testimony whereof I have hereunto affixed my signature.

FRANK M. MORTON.
